UNITED STATES PATENT OFFICE.

GEORGE W. NÜTZ, OF CHICAGO, ILLINOIS.

FILTER.

No. 907,636.

Specification of Letters Patent.

Patented Dec. 22, 1908.

Application filed September 16, 1907. Serial No. 392,972.

To all whom it may concern:

Be it known that I, GEORGE W. NÜTZ, a citizen of the United States of America, and a resident of Chicago, in the county of Cook and State of Illinois, have invented certain new and useful Improvements in Filters, of which the following is a specification.

This invention relates to that class of filters in which an annular filtering septum of fibrous material is employed; and the present improvement has for its object to provide a simple and efficient structural formation and combination of parts by means of which a constant cleaning of the inner or induction 10 surface of the filtering septum is automatically effected during actual use, and which in addition affords a substantial and economical assemblage of parts, all as will hereinafter more fully appear.

20 In the accompanying drawings:—Figure 1, is a side elevation of a filter embodying the present invention. Fig. 2, is a horizontal section of the same, on line $x-x$, Fig. 1. Fig. 3, is a vertical section of the same on line $x'-x'$ Fig. 2. Fig. 4, is a detail perspective view of one of the holding clips.

Similar numerals of reference indicate like parts in the different views. Referring to the drawings, 1 represents the 30 filter housing, preferably of the inverted bell form shown, and 2 is the closure head for the open top of said housing. To such end the head is formed with an annular recess 3 for the reception of the corresponding top rim of 35 the housing and for an interposed packing ring 4, as shown.

5, is the inlet neck, and 6 the outlet neck of the filter; such necks are formed integral with the closure head 2, and are arranged in 40 horizontal alinement one with the other and overhang said head to receive the induction and excretion connections of the filter, as well as to afford an attachment for the connecting yoke hereinafter described.

45 7, is a depending annular rim or enlargement on the underside of the closure head 2, for the attachment of the annular filtering septum hereinafter described, and to such end said rim is provided with an out-turned flange 8 at its lower end.

9 is a spring ring or clip encircling the filtering septum above the aforesaid flange and adapted to hold the same in place, and yet afford a ready detachment of parts when required.

55 10, is a vertical branch passage formed in

the rim or enlargement 7 and connecting the passage of the inlet neck 5 with the interior of the filtering septum.

11, is a companion vertical branch passage 60 formed in the closure head 2, and connecting the passage of the outlet neck 6 with the interior of the housing 1 at a point in the exterior of the filtering septum.

12, is the filtering septum above referred to and which consists of a cylindrical shell of leather or like porous material, the upper end of which is attached in the manner above set forth to the depending rim or enlargement 7 of the closure head, while its lower end is attached in a substantially similar manner to a tensioning head now to be described.

13, is a loose tensioning or weighted head arranged loosely within the filter housing and adapted to have free movement therein un- 75 der a jolting of the filter in a use of the same upon motor vehicles and the like and for the purpose hereinafter stated.

14, is an out-turned flange near the upper end of the head 13, and 15 is a spring ring or 80 clip securing the filtering septum to the head below said flange and adapted to hold the septum in place and yet afford a ready detachment of the parts when required.

With the above described arrangement of 85 parts the filtering septum 12 and its tensioning head 13 hangs loosely within the chamber of the filter housing 1, and free to move therein in response to the jolting of the filter when used upon an automobile or the like. 90 Such jolting action, it has been found from practical experience imparts an undulating movement to the septum which is adapted to dislodge in a very effective manner any solid matter from the induction surface of 95 the septum, and cause such matter to descend and accumulate upon the head 13 and the immediately adjacent portion of the septum leaving the main portion of the septum clean during a long continued use. 100

16, is the connecting yoke above referred to, of a U shape with the upper ends of its parallel arms formed with counterpart eyes 17 adapted to fit over the overhanging portions of the inlet and outlet necks 5 and 6; 105 the construction being such that said arms can be sprung apart and the aforesaid eyes slipped over the necks 5 and 6 and then pressed into place to afford a pivotal connection between said yoke and the closure head 110 of the filter. As so arranged the yoke and closure head are always connected and there

is no liability to detachment and loss of the parts. To permit of the assemblage of parts in the manner above set forth, the eyes 16 and 17 will be of the flaring form shown in Fig. 2, in order to readily pass over the respective necks of the closure head.

18, is a clamping screw passing centrally through the bottom part of the yoke 15 and having bearing against the central and lower portion of the filter housing 1, and so that by an adjustment of said screw the filter housing is forced and held to its before described bearing in the closure head 2.

Having thus fully described my said invention what I claim as new and desire to secure by Letters Patent, is:—

1. In a filter, the combination of a housing, an annular filtering septum suspended within said housing by its upper end, a weighted head attached to the lower end of said septum and forming a closure therefor, an inlet passage connecting with the interior of said septum; and an outlet passage connecting with the interior of the housing, substantially as set forth.

2. In a filter, the combination of a housing, an annular filtering septum suspended within said housing by its upper end, a weighted head attached to the lower end of said septum and forming a closure therefor, an inlet passage connecting with the interior of said septum at its upper end, and an outlet passage connecting with the interior of the housing at its upper end, substantially as set forth.

3. In a filter, the combination of a housing, an annular filtering septum suspended within said housing by its upper end, a weighted head attached to the lower end of said septum and forming a closure therefor, a spring ring encircling said septum and securing the same to the weighted head, an inlet passage

connecting with the interior of said septum, and an outlet passage connecting with the interior of the housing, substantially as set forth.

4. In a filter, the combination of a housing, an annular filtering septum suspended within said housing by its upper end, a weighted head attached to the lower end of said septum and forming a closure therefor, a spring ring encircling said septum and securing the same to the weighted head, an inlet passage connecting with the interior of said septum at its upper end, and an outlet passage connecting with the interior of the housing at its upper end, substantially as set forth.

5. In a filter the combination of an open top housing, a closure head fitting the top of said housing and provided with inlet and outlet necks and with a depending rim, an annular filtering septum attached at its upper end to said rim, and a spring ring encircling the septum and securing the same to said rim, substantially as set forth.

6. In a filter the combination of an open top housing, a closure head fitting the top of said housing and provided with inlet and outlet necks arranged in horizontal alinement, a single piece connecting yoke having eyes at the upper ends of its arms adapted to engage over the necks aforesaid, and a clamping screw passing through the lower end of said yoke and bearing against the underside of the housing, said yoke being adapted to be sprung apart to receive said necks in an assemblage of the parts, substantially as set forth.

Signed at Chicago, Illinois, this 13th day of September 1907.

GEO. W. NÜTZ.
